UNITED STATES PATENT OFFICE.

ARTHUR J. RAY, OF CHICAGO, AND HERBERT F. OBERGSELL, OF AUSTIN, ILLINOIS, ASSIGNEES TO AUTOMATIC ELECTRIC COMPANY, OF CHICAGO, ILLINOIS, A CORPORATION OF ILLINOIS.

AUTOMATIC TELEPHONE SYSTEM.

Application filed September 20, 1920. Serial No. 411,568.

To all whom it may concern:

Be it known that we, ARTHUR J. RAY and HERBERT F. OBERGSELL, both citizens of the United States of America, and residents of Chicago, Cook County, Illinois, and Austin, Cook County, Illinois, respectively, have invented certain new and useful Improvements in Automatic Telephone Systems, of which the following is a specification.

10 Our invention relates in general to automatic telephone systems in which connections are established through the medium of subscriber controlled automatic switches, but is more particularly concerned with such 15 automatic systems as include party lines and selective ringing equipment at the exchange; and the object of the invention may be stated in general terms to be the provision 20 of a new and improved automatic party line selective ringing system.

A number of different methods of selectively signalling the stations on the party lines have been practiced before this. One method which has been used to some extent 25 involves a provision of a small auxiliary switch for each party line connector. Any station on a party line may be called from any one of the connectors which have access to that particular line, and the auxiliary 30 switch is operated either before or after the associated connector is operated in order to select ringing current of the proper character to signal the station desired. Thus it will be seen that there may be as many stations on 35 a party line as there are different kinds of ringing current provided at the exchange, which usually does not exceed five. If it is desired to connect a greater number of stations on a party line, ten stations, for 40 example, the party line may be connected in multiple to two sets of bank contacts in the connector banks, and the ringers at the ten sub-stations are connected half from each side of the line to ground. With this 45 arrangement, and assuming that the lines are reversed between the two sets of bank contacts, half the stations on the line may be signalled by calling one set of bank contacts and the other half may be signalled by 50 calling the other set of bank contacts. This arrangement is very satisfactory, so far as the operation thereof is concerned; but it is also uneconomical, since it reduces by one half the number of party lines which may be

handled by the group of connector switches. 55 The object of our invention, stated specifically, is to provide a selective signalling system of the general type described above which is adapted to signal twice the number of stations on a party line as there are 60 different kinds of ringing current at the exchange, without, however, requiring that each party line be connected to two sets of bank contacts. We are thus able to double the number of party line stations which can 65 be reached from a single group of connector switches.

There are other minor improvements which together with the above will be described fully hereinafter, reference being 70 had to the accompanying drawing.

Referring to the drawing, which comprises a single sheet, we have shown therein sufficient of the apparatus in an automatic telephone system to enable our invention to 75 be explained and understood. The reference character A indicates an automatic substation of the usual type, which has the usual talking instrumentalities and the calling device S for controlling the central 80 office switches.

Substation A is connected with the central exchange by line conductors 11 and 12 which terminate in the individual line or trunk selecting switch C. The line switch C is a 85 switch of the well known rotary type whose wipers have no normal position and move in a forward direction only. As is well known the function of the individual line switch is to extend its associated line to an 90 idle first selector switch when the receiver is raised at the substation to initiate a call. One of the first selector switches to which the line switch C has access in common with other similar line switches is indicated in the 95 drawing by the rectangle D. Inasmuch as selector switches are well known in the art it has not been considered necessary to show the circuits in detail. It may be stated briefly that the selector D is a Strowger vertical and rotary switch of well known mechanical construction and operable according to the two wire system of control. When used in setting up a connection the selector responds to the first digit in the 100 called number in order to select a desired group of connector switches, after which the selector automatically rotates to select and 105

connect with a trunk line extending to an idle connector in the selected group. The above is of course true only of a 1000 line system; if the capacity of the system is greater than this, second or third selectors will be interposed between the first selectors and connectors in the well understood manner. This is the usual percentage trunking system, however, and need not be discussed in detail.

One of the trunk lines which the selector D has access to is shown in the drawing as extending to the connector E, which is also a Strowger vertical and rotary switch having a capacity of 100 subscribers' lines. The connector E is operable according to the two wire system of control like the selector D, and it responds to the last two digits in a called number to complete the connection to the called line.

One of the lines to which the connector E has access is shown at the upper right hand corner of the drawing and comprises line conductors 101 and 102. This line is a party line, and substations A¹-A¹⁰, inclusive, only one of which is shown completely, are connected in bridge of the line in the usual manner. The line switch C' is associated with the party line at the exchange and is similar to the line switch C.

Just below the connector E we have shown an auxiliary switch which is indicated by reference character F. This is the switch referred to in the foregoing and when used in the present situation is generally called a frequency selecting switch. It comprises briefly, the wipers 122 and 123, and associated sets of bank contacts, the stepping magnet 120, and the release magnet 121. The frequency selector F is individual to the connector E. The circuit arrangement whereby the two switches can operate in selectively signalling any one of the ten stations on the party line shown or another similar party line is the principal subject matter of the invention and will now be described.

For this purpose it will be assumed that the subscriber at substation A desires to establish connection with the subscriber at substation A¹⁰. When the receiver is removed at the calling station a circuit is completed over the conductors 11 and 12 for the line relay 15. Upon energizing, relay 15 closes a circuit at its armature 20 which includes the winding of the switching relay 14 and the stepping magnet 16 in series; and at its armature 21 connects the test wiper 26 to the above circuit at a point midway between the said switching relay and the magnet. The operation now depends upon whether the trunk line with which the line switch wipers are associated is busy or is not busy. If the trunk line is busy there will be a ground potential upon the test contact with which the test wiper 26

is in engagement, the switching relay 14 will be short circuited, and the stepping magnet 16, which interrupts its own circuit, will be operated in the manner of a buzzer to advance the switch wipers in search of an idle trunk line. However, we may assume in the present case that when the call is initiated the trunk line upon which the wipers of the line switch are standing is idle. Under these circumstances when the line relay 15 is energized the switching relay 14 will not be short circuited and the stepping magnet 16 will not be operated because of the high resistance of the said switching relay. The latter relay, however, is energized, grounds the test wiper 26 at its armature 18, and at its armatures 17 and 19 disconnects the line conductors 11 and 12 from the windings of the line relay 15 and from ground, respectively, and extends them by way of wipers 25 and 27, and bank contacts 28 and 30 to the line relay (not shown) of the first selector D. The line and release relays of the selector D are now energized in the usual manner and the latter relay grounds the release trunk conductor of the trunk line in order to establish a holding circuit for the switching relay 14 of the line switch C. This operation is well understood and need not be explained further.

The calling subscriber may now operate his calling device in accordance with the first digit in the desired number. In response to the interruptions in the line thus produced the vertical magnet of the selector D is operated under control of the line relay to raise the wipers 40-42, inclusive, to the particular level in which are terminated the trunk lines extending to the desired group of connector switches. Thereafter the rotary or trunk selecting movement is initiated automatically in the usual manner and the wipers are rotated in search of an idle trunk line. Assuming that the trunk line shown in the drawing is the first idle trunk line when the wipers arrive at bank contacts 43-45, inclusive, the test wiper 41 will find no ground potential upon the test contact 44 and the rotation of the switch will cease. When this occurs the incoming line conductors are extended in the usual manner by way of the switch wipers 40 and 42, bank contacts 43 and 45, and contact springs controlled by the reversing relay 50 to the windings of the double wound line relay 51 of the connector E.

When the line is extended as above described the line relay 51 is energized over the line circuit to close a circuit for the slow acting release relay 52. Upon energizing, relay 52 prepares a circuit for the vertical magnet 58 at its armature 65, and at its armature 66 connects ground to the release trunk conductor 47, thereby completing a holding circuit for the selector D and the

line switch C in the well known manner. The calling subscriber may now operate his calling device in accordance with the next digit in the desired number. As a result 5 the line relay 51 is deenergized a plurality of times, and at the first deenergization transmits a current impulse to the vertical magnet 58 over the following circuit: from ground at G², by way of armature 64 and 10 its resting contact, armature 65 and its working contact, off normal springs 61 and 63, winding of the slow acting series relay 53, and the winding of the vertical magnet 58 to battery. By the operation of the vertical magnet the wipers 90-92, inclusive, are raised step by step until they stand opposite the level in which is terminated the line of 15 substation A¹⁰. The slow acting series relay 53 is energized in series with the vertical magnet and by means of its armature 67 maintains the circuit of the vertical magnet intact after the off normal springs have been shifted, which occurs on the first vertical step. At the end of the vertical movement 20 of the switch, relay 53 is deenergized and transfers the operating circuit to the rotary magnet 59.

The subscriber will now operate his calling device in accordance with the next digit 30 of the desired number, which is the last digit which has to do with the line selection. When the calling device is operated the line relay 51 responds as before and sends impulses to the rotary magnet 59 over the following circuit: ground at G², armature 64 and its resting contact, armature 65 and its working contact, off normal springs 61 and 62, armature 67 and its resting contact, resting contact of armature 72 and the said 35 armature, winding of the slow acting series relay 56, armature 81 and its resting contact, and the winding of the rotary magnet 59 to battery. By the operation of the rotary magnet the wipers 90-92, inclusive, are 40 rotated step by step and are finally brought to rest in engagement with the bank contacts in which the line of substation A¹⁰ is terminated, these bank contacts being indicated in the drawing by reference characters 45 93, 94, and 95. The slow acting relay 56 is energized in series with the rotary magnet and retains its armature attracted throughout the rotary movement of the switch. At 50 its armature 74, relay 56 connects the test wiper 91 with the test relay 55, and at its armature 75 the said relay 56 closes a shunt around the contact at armature 72 of the test relay. The latter operation is to prevent the test relay from opening the 55 rotary magnet circuit while the test wiper is passing over busy test contacts.

It will be assumed, first, that the called line is busy. Such being the case, when the test wiper 91 arrives at test contact 94 it 60 will find a ground potential thereon, the

test relay 55 will be energized, and when the slow acting relay 56 deenergizes at the end of the rotary movement the test relay 55 establishes a locking circuit for itself at its armature 71. Relay 55 also opens the 70 rotary magnet circuit at its armature 72, and at its armature 73 connects a lead from the busy signalling machine to the lower heavy talking conductor. By this operation an audible signal is transmitted to the calling subscriber and being advised thereby that the called line is inaccessible for the time being he will hang up his receiver.

Having explained the operations which take place when the called line is busy it will now be assumed that the line is idle when called. Under these circumstances when the test wiper 91 arrives at test contact 94 it will find no ground potential and the test relay 55 will not be energized. Then when the slow acting relay 56 deenergizes at the end of the rotary movement of the switch a circuit is completed for the switching relay 57 as follows: from the grounded release trunk conductor 47 by way of armature 71 and its resting contact, upper winding of the switching relay 57, resting contact of armature 74 and the said armature, test wiper 91, test contact 94, winding of the switching relay 14', and the winding of the stepping magnet 16' to battery. Relays 57 and 14' are energized in series over the above circuit, and the latter relay is operated to clear the called line of its normal battery and ground connections in the line switch C'. It is noted that the relay 14' is not fully operated at this time, due to a mechanical interlocking arrangement between the armature of its relay and the armature of the line relay 15', and the wipers of the line switch C' are not connected up. In the connector E, when the switching relay 57 is energized it establishes a locking circuit for itself at its armature 80, opens the circuit of the test relay 55 at its armature 79, grounds the test wiper 91 at its armature 78, transfers the operating circuit to the stepping magnet 120 of the frequency selecting switch F at its armature 81, closes a circuit at its armature 82 which provides for transmitting a tone signal to the calling subscriber during the ringing operation, and at its armatures 77 and 83 completes the connection to the line wipers 90 and 92.

The calling subscriber may now operate his calling device in accordance with the final digit in the number, which is the digit which selects the proper frequency of ringing current for signalling the particular station wanted. The substations A¹-A¹⁰, inclusive, have been numbered for convenience in accordance with the digits to which they correspond, and since the substation A¹⁰ is the wanted substation in the present case

the final digit to be called will be the digit 0. When the calling device is operated for this digit the line relay 51 transmits ten impulses of current to the stepping magnet 120 of 5 the frequency selector F over the following circuit: from ground at G², by way of armature 64 and its resting contact, armature 65 and its working contact, off normal springs 61 and 62, armature 67 and its resting contact, resting contact of armature 72 and the said armature, winding of slow acting series relay 56, armature 81 and its working contact, armature 87 and its resting contact, and the winding of the stepping magnet 10 120 to battery. By the operation of magnet 120 wipers 122 and 123 are given a step by step movement and are finally brought to rest in engagement with the tenth contacts in their respective banks. The slow acting 15 relay 56 is energized in series with the magnet 120, but without effect so far as the connector E is concerned. At the end of the series of impulses transmitted to the magnet 120 relay 56 is deenergized and a circuit is completed for relay 89 as follows: ground at G³, wiper 122, tenth contact in the bank associated with said wiper, conductor 135, winding of the reversing relay 96, armature 20 76 and its resting contact, and the winding of relay 89 to battery. By the closure of the above circuit relays 96 and 89 are energized in series and the former relay, by means of armatures 84 and 85, reverses the connections to the line wipers 90 and 92 in an obvious manner. Relay 89, upon energizing, 25 breaks the circuit of the stepping magnet 120 at armature 87, prepares a circuit for the release magnet 121 at armature 86, and at armature 88 completes the signalling circuit as follows: from the grounded generator Gen, through the contact of the ringing interrupter, conductor 130, tenth contact in the bank associated with wiper 123, wiper 40 123, conductor 137, armature 88 and its working contact, resting contact of armature 70 and the said armature, working contact of armature 83 and the said armature, working contact of armature 84 and the said armature, wiper 90, bank contact 93, conductor 101, the normally closed switch hook contact at substation A¹⁰, and the ringer at 45 the said substation to ground. The above circuit is intermittently opened and closed by the operation of the ringing interrupter and the ringer at substation A¹⁰ is thus 50 operated at intervals to signal the called subscriber. It is understood of course, that the ringing current also flows through the ringers at substations A⁶-A⁹, inclusive to ground at the same time, but the ringers at these other substations are tuned so that they will not respond to the frequency of ringing current which is now in use. This 55 is according to the well known practice of harmonic signalling, and it follows that the

ringer at substation A¹⁰ is the only one which is operated. When the called subscriber at substation A¹⁰ removes his receiver to answer the call the ringer thereat is disconnected and the ringing circuit is completed over a metallic circuit including the other line conductor 102 and the upper winding of the ring cut off relay 54 at the connector E. The ring cut off relay 54 is now energized and establishes a locking circuit for itself at its armature 69, opens the ringing circuit at its armatures 68 and 70, and at the working contacts of these same armatures finally completes the talking circuit. 60

The required connection has now been established and the calling and called subscribers may converse as desired. Current for the transmitter at substation A is supplied through the windings of the double wound line relay 51 while current for the transmitter at substation A¹⁰ is supplied through the windings of the back bridge or reversing relay 50. The latter relay is of course energized and reverses the direction 65 of current flow in the calling line during conversation. Although this operation is of no utility in connection with the apparatus shown it is a standard operation for use in controlling measured service equipment 70 and is therefore included. When the conversation is finished both subscribers will hang up their receivers. When the receiver is replaced at substation A the line and release relays 51 and 52 are deenergized and the latter relay closes a circuit for the release magnet 60, which operates to restore the connector E to normal position in the usual manner. Relay 52 also disconnects ground from the release trunk conductor 47, thereby breaking the holding circuits of the selector D and line switch C and these two switches are accordingly restored to normal 75 also. At the same time that relay 52 closes the circuit of release magnet 60 said relay 80 closes a circuit by way of armature 86 of relay 89 which includes the release magnet 121 of the frequency selecting switch F. By the operation of the release magnet 121 the holding and driving pawls are withdrawn 85 from the ratchet of switch F and the wipers are restored to normal position. Thus all the apparatus in use has been freed and made ready for use in another connection. 90

A brief explanation will now be given of 95 the manner in which the other stations on the line are signalled. Substations A⁶, A⁷, A⁸, and A⁹, may be reached by calling digits 6, 7, 8, and 9, respectively, as the final digits, and the operations are exactly the same as 100 when substation A¹⁰ is called except that a different frequency of ringing current is selected. It will be understood in this connection that conductors 130-234, inclusive, all 105 extend to separate ringing current genera- 110

tors, and these generators are all of different frequency. Although only one of these generators is shown in the drawing it is believed that this explanation will make the

arrangement perfectly clear. The ringers at the five substations just referred to are all connected from the line conductor 101 to ground. In order to operate the ringers at the remaining stations, substations A'-A⁵, inclusive, which are connected from the line conductor 102 to ground, digits 1, 2, 3, 4, and 5, respectively, must be called as the final digits. Suppose, for example, that it is desired to call the substation A⁵, the ringer at which station is tuned to the same frequency as the ringer at substation A¹⁰ but which is connected from the line conductor 102 to ground. The final digit to be called in this case is the digit 5 and the wipers of the frequency selector F are advanced five steps into engagement with the fifth contacts in their respective banks. When relay 56 deenergizes at the end of the operation of the frequency selecting switch a circuit is closed for the relay 89 the same as before, except that in the present case the circuit is established over conductor 136 and does not include the reversing relay 96. By the movement of wiper 123 the ringing generator shown in the drawing is selected, the first five contacts in the bank associated with wiper 123 being connected in multiple with the last five, and when relay 89 energizes a ringing circuit is completed substantially the same as previously described except that in the present case the ringing current is applied to the line by way of wiper 92 instead of wiper 90, and hence flows over the line conductor 102 and through the ringers at substations A'-A⁵, inclusive, to ground. The ringer at substation A⁵ is accordingly operated. Substations A' to A⁴, inclusive, may be called in the same manner by using the final digits which correspond to these substations.

It will be seen that by providing a reversing relay in each connector switch we are able to double the number of stations on the line without having to use two sets of contacts for such line in the connector banks.

The reversing relay performs the same function as the reversal in the line conductors between the two sets of bank contacts and the required result is thus accomplished in a simpler and more economical manner.

Having described our invention, what we consider to be new and desire to have protected by Letters Patent will be pointed out in the appended claims.

60 What we claim as our invention is:

1. In a selective ringing telephone system, party lines, a connector switch provided with frequency selecting means, there being only half as many different frequencies of ringing current to be selected as there

are stations on a party line, and means in said connector cooperating with said frequency selecting means whereby all the stations on a party line may be selectively signalled, said means comprising a frequency selecting mechanism and a separate line conductor reversing device. 70

2. In a telephone system, a party line, substation ringers connected from opposite sides of said line to ground, an automatic switch for extending a connection to said line, said switch including a pair of line wipers, a plurality of sources of ringing current of different character there being half as many of said sources as there are stations on said line, means associated with said switch for selecting one of said sources, and means separate from the last named means for connecting the selected source to either of said wipers. 80

3. In a telephone system, different sources of ringing current at the exchange, a party line, substation ringers equal in number to the number of said sources connected from one side of said line to ground, a like number of ringers connected from the other side of said line to ground, means including an automatic connector switch for extending a connection to said line, means associated with said connector for selecting any one of said sources, and means operable thereafter for controlling the connecting of the selected source to either side of said line to signal any desired station thereon. 90

4. In a telephone system, different sources of ringing current at the exchange, a party line, substation ringers equal in number to the number of said sources connected from one side of said line to ground, a like number of ringers connected from the other side of said line to ground, means including an automatic connector switch for extending a connection to said line, and two selecting devices operable successively thereafter for selecting any one of said sources and for connecting the selected source to either side of the connected line to signal any desired station thereon. 100

5. In a telephone system, a party line, a plurality of stations and ringers thereat connected from opposite sides of said line to ground, a plurality of different ringing current sources at the exchange equal in number to half the number of said stations, an automatic connector switch at which said line terminates in a single set of bank contacts, means for operating said connector to connect with said contacts, a frequency selector for then selecting any one of said current sources, and a second selecting device actuated after said frequency selector has operated for connecting the selected source to either side of said line to signal any desired one of said stations. 115

6. In a telephone system, a party line, a 120

plurality of stations and ringers thereat connected from opposite sides of said line to ground, a plurality of different frequency ringing current sources at the exchange equal in number to half the number of said stations, an automatic connector switch at which said line terminates in a single set of bank contacts, means for operating said connector to connect with said contacts, and means for then selecting any one of said current sources and connecting the same to either side of said line to signal any desired one of said stations, said means comprising a reversing relay in said connector and a frequency selecting switch including means for controlling said relay.

7. In a telephone system, a partly line, a plurality of stations and ringers thereat connected from opposite sides of said line to ground, a plurality of different frequency ringing current sources at the exchange equal in number to half the number of said stations, an automatic connector switch at which said line terminates in a single set of bank contacts, means for operating said connector to connect with said contacts, a frequency selecting switch associated with said connector for selecting any one of said current sources, and a relay in said connector controlled by said frequency selecting switch for connecting the selected source to either side of said line to signal any desired one of said stations.

8. In a telephone system, a partly line, a plurality of stations and ringers thereat connected from opposite sides of said line to ground, a plurality of different frequency ringing current sources at the exchange equal in number to half the number of said stations, an automatic connector switch at which said line terminates in a single set of bank contacts, means for operating said connector to connect with said contacts, a frequency selecting switch associated with said connector for selecting any one of said current sources, and a reversing relay in said connector for connecting the selected current source to either side of said line to signal any desired one of said stations.

9. In a telephone system, a connector switch, a line accessible thereto, a plurality of sources of ringing current, a selecting device, means for extending a connection to said line by way of said connector switch, means for operating said selecting device

to select any one of said sources of current, a relay, a second relay, a circuit for the first relay including said second relay, a second circuit for said first relay exclusive of said second relay, and means controlled by said selecting device for closing one or the other of said circuits so as to apply ringing current from the selected sources to one side or the other of the called line.

10. In a telephone system, a connector switch, a line accessible thereto, a plurality of sources of ringing current, a selecting device, means for extending a connection to said line by way of said connector switch, means for operating said selecting device to select any one of said sources of current, a relay, a second relay, means for applying ringing current from the selected source to one side of the called line by energizing the first relay alone, and means for applying ringing current to the other side of the called line by energizing both of said relays together.

11. In a telephone system, a connector switch, a line accessible thereto, a plurality of sources of ringing current, a selecting device, means for extending a connection to said line by way of said connector switch, means for operating said selecting device to select any one of said sources of current, a relay, a second relay, means for applying ringing current from the selected source to one side of the called line by energizing the first relay alone, and means for applying ringing current to the other side of the called line by energizing both of said relays together, both of said applying means being controlled by the position of said selecting device.

12. In a telephone system, a connector switch, a line accessible thereto, a plurality of sources of ringing current, a selecting device, means for extending a connection to said line by way of said connector switch, means for operating said selecting device to select any one of said sources of current, a relay, a second relay, means for applying ringing current from the selected source to one side of said line by energizing the first relay alone, and means for applying said ringing current to the other side of said line by energizing both of said relays in series.

Signed at Chicago, Cook County, Illinois, this 17th day of September, 1920.

ARTHUR J. RAY.
HERBERT F. OBERGFELL.
